CLAIM

The ornamental design for neckwear, as shown and described.

DESCRIPTION

FIG. 1 is a front perspective view of a neckwear showing my new design;

FIG. 2 is a front elevational view thereof;

FIG. 3 is a top plan view thereof;

FIG. 4 is a rear elevational view thereof; and,

FIG. 5 is an end elevational view thereof, the opposite end is a mirror image.

The broken line showing of the human form in FIG. 1 is for illustrative purposes only and forms no part of the claimed design.
